UNITED STATES PATENT OFFICE.

JACK LADER, OF BROOKLYN, NEW YORK, ASSIGNOR TO C. R. WHITING CO., OF NEWARK, NEW JERSEY, A COPARTNERSHIP COMPOSED OF VICTOR FRIEDLANDER AND FRANK V. FRIEDLANDER.

DESIGN FOR LINING PAPER OR SIMILAR ARTICLE.

Application filed November 18, 1926. Serial No. 19,762. Term of patent 3½ years.

To all whom it may concern:

Be it known that I, JACK LADER, a citizen of the United States of America, residing at 436 Eastern Parkway, Brooklyn, in the county of Kings and State of New York, have invented a new, original, and ornamental Design for Lining Paper or Similar Articles, of which the following is a specification, reference being had to the accompanying drawing, forming part thereof.

The figure is a plan view of a piece of paper or similar article showing my design.

I claim:

The ornamental design for lining paper or similar article, as shown.

Dated at New York city, N. Y., this 28 day of October 1926.

JACK LADER.
